UNITED STATES PATENT OFFICE.

JAMES M. BLASHFIELD, OF JACKSON, MICHIGAN, ASSIGNOR OF ONE-HALF TO
THEOPHILUS SCOTT, OF JACKSON, MICHIGAN.

HOT-AIR FURNACE.

1,125,449.

Specification of Letters Patent. Patented Jan. 19, 1915.

Application filed March 28, 1914. Serial No. 827,934.

To all whom it may concern:

Be it known that I, JAMES M. BLASHFIELD, citizen of the United States, residing at Jackson, in the county of Jackson and State of Michigan, have invented certain new and useful Improvements in Hot-Air Furnaces, of which the following is a specification.

My invention relates to furnaces, and particularly to furnaces adapted for heating buildings.

The invention has relation to the type of hot air furnaces comprising an inner flue, an outer wall forming a space between the inner flue and wall and means for controlling the passage of air through such space for regulating the burning of the fuel.

The invention has for its object to devise a heating furnace of the type hereinbefore stated embodying a novel structural arrangement and to minimize the number of joints as well as to provide an arrangement which admits of the parts being easily and quickly assembled and retained in the required position without necessitating the use of fastening means.

A further purpose of the invention is the provision of a hot air furnace embodying a maximum amount of heating surface, thereby economizing in the consumption of fuel and insuring a rapid heating of the air passing through the furnace on its way to the apartments or places to be heated.

The invention consists of the novel features, details of construction and combinations of parts which hereinafter will be more particularly set forth, illustrated in the drawings and pointed out in the appended claims.

My invention is illustrated in the accompanying drawings wherein:

Figure 1 is a perspective view of a furnace constructed in accordance with my invention. Fig. 2 is a diametrical section through the furnace on the line 2—2 of Fig. 3. Fig. 3 is a transverse section on the line 3—3 of Fig. 2. Fig. 4 is a fragmentary section on the line 4—4 of Fig. 2. Fig. 5 is a top plan view of the oscillating grate. Fig. 6 is an edge elevation of the oscillating grate. Fig. 7 is a plan view of the septum or plate 15.

Corresponding and like parts are referred to in the following description and indicated in all the views of the accompanying drawings by the same reference characters.

Referring to these drawings, it will be seen that my improved furnace comprises an outer casing 2 which is preferably of sheet metal. Disposed centrally within this outer casing is a vertical air flue or chamber 3 which extends nearly up to the top of the casing but discharges into a distributing air chamber 4. The upper and lower ends of this central air flue are open and the lower end of the air flue 3 opens into a receiving air chamber 5 disposed in the floor of the basement in which the heating furnace is located. This receiving air chamber 5 is of course connected to any suitable source of air, as for instance the air exterior to the building.

Disposed concentrically to the wall 6 of the air chamber 3 and spaced therefrom is the wall 7 which surrounds the ash-pit 8, the fire-pot 9 and the smoke chamber 10. Preferably this wall 7 is formed of cast sections. The lower end of the ash-pit space 8 is closed by the inwardly turned flange 11 of the wall 7, the wall 6 of the central air flue 3 being provided with an annular shoulder 12 which rests upon the flange 11. The ash-pit 8 is separated from the fire-pot 9 by a grate. This grate is annular in form and comprises the oscillatable section 13 and the relatively fixed section 14 whose construction will be later described.

The upper end of the annular fire-pot 9 is separated from the smoke chamber 10 by a septum 15 formed adjacent the central flue 6 with a plurality of openings 16. This septum 15 at its inner edge rests upon an annular shoulder 17 formed upon the wall of the air flue 3 and at its outer edge is flanged and bolted to the upper end of the wall 7 as at 18. The upper end of the space between the wall 7 and the wall 6 is closed by an annular upwardly bowed casting 19, the inner and outer edges of which are rabbeted to engage over the upper ends of the walls 6 and 7. This cap or casting 19 prevents the passage of products of combustion from the combustion chamber into the air distributing chamber 4. A deflector 20 is disposed above the upper end of the air flue 3 in spaced relation to the upper end of the wall 6. This deflector as illustrated is concavo-convex, the convex side of the deflector being downward and is supported upon a plurality of legs 21, these legs being outwardly and downwardly extended and

bolted or otherwise attached to the casting 19. This deflector acts to impede the too rapid passage of the air through the air chamber 3 and distributes the air evenly in the distributing air chamber 4.

A thimble 22 enters the wall 2 at the back of the furnace and extends through the air space encircling the fire-pot and has smoke-tight engagement with the wall 7 just above the level of the septum 15. From this relatively short thimble 22 a smoke pipe 23 extends by which the products of combustion are carried away. The smoke chamber 10 is also connected with the front of the furnace by a thimble 24 as illustrated in dotted lines in Fig. 1, this thimble being closed at its outer end by means of a cap 25. This open end of the thimble 24 forms a clean-out opening whereby access may be had to the smoke chamber 10.

Extending from the upper end of the ash-pit 8 just above the grate support and disposed in the air space between the wall 2 and the wall 7 is a dust flue 26. The lower end of this dust flue is connected to the ash-pit space by an elbow 27. The upper end of the flue is connected with the thimble 24 by the downwardly turned flange 28. A damper 29 is disposed in this flue 26, the damper being controlled by means of a spindle 30 projecting to the front of the furnace.

The grate as before stated consists of two sections, one fixed and one oscillating. The fixed section of the grate which is designated 14 is formed in two sections and is annular in form. At its inner edge this fixed section is formed with a flange 31 which rests upon an annular shoulder 32 formed upon the wall 6. A shoulder 33 also formed upon the wall 6 in spaced relation to the shoulder 32 bears upon the upper face of the inner margin of the fixed section 14. The outer margin of the fixed grate section is held to the wall 2 by bolts 34 in the manner shown clearly in Fig. 2.

Disposed just below the fixed section 14 is the oscillatable section 13 which rests upon its inner margin upon a shoulder 35 formed upon the wall 6 and at its outer margin rests upon a ring 36 bolted to the wall 7. The oscillatable section 13 as illustrated in Figs. 3, 4 and 5, comprises a plate formed in two sections, these sections being designated respectively 13^a and 13^b and this plate is provided with a plurality of radially disposed slots 37. The sections 13^a and 13^b are held to each other by bolts 38 which pass through downwardly extending facing lugs or flanges 39 formed upon the under faces of the sections 13^a and 13^b.

The oscillatable grate 13 is formed with a socket 40 which projects out through a slot 41 formed in the wall 7 as shown clearly in Fig. 4 and is adapted to receive a handle 42 which extends to the exterior of the furnace.

The slot 41 is closed by a shield 43 which is attached to the socket 40 and which is of such length that the lever 42 may be oscillated to the full extent on the slot 41 without the slot 41 being at any time uncovered.

The fixed section 14 as shown in Fig 3 consists of an annular plate formed with radiating arms 44, these arms defining relatively large openings 45 between the arms. There are relatively few of these arms in comparison with the number of slots in the oscillating plate 13.

The operation of this grate is as follows. Upon an oscillation of the handle 42, the grate section 13 will be oscillated and the coal which is supported upon the grate section 13 as this grate section is oscillated, will ride over the arms 44 so that the arms will tend to shift the coal and distribute it upon the upper face of the grate section 13 and will tend to shake the coal up. The ashes, clinkers, etc., shaken from the coal will sift down through the slots 37 into the ash-pit 8. I find that by the use of this particu-

lar form of grate, I can secure a thorough distribution of the coal upon the grate and prevent any tendency of the coal to clinker. In order to provide for charging the furnace with coal, I provide two coal chutes 46 disposed on the same level and extending approximately tangential to the axial center of the grate surface.

In other words, the adjacent walls of the two coal chutes extend approximately radially while the outer walls extend tangentially. Thus the coal chutes are relatively wide and permit coal to be thrown into the fire-box and to be discharged entirely around the grate surface even to a point behind the central flue. It

will be obvious that if only one coal chute is provided, disposed in the ordinary position in front of the furnace and extending radially to the axis of the furnace, the coal could not be readily distributed upon the annular grate. With this arrangement,

however, I dispose the openings of the coal chutes at the most convenient point, that is, both at the front of the furnace, and yet am able to secure a proper distribution of the coal upon the grate. This proper distribution of coal is, of course, aided by the curvature of the wall 7 which tends to deflect coal thrown into the chutes 46 around to the back portion of the grate. I also pro-

vide a pair of ash-pit chutes 48^a opening from the front of the furnace into the ash-pit 8, and likewise located each at a tangent to the axial center of the furnace, these ash-pit chutes being located in alinement with the chutes 46 and extending inward from the front of the furnace to the ash-pit 8.

The chutes 46 are closed by doors 47 of any suitable character and shown as hinged doors. It will be noted that the outer ends of the chutes 46 are flush with the exterior

wall of the furnace and that the doors 47 are slightly curved to suit the curvature of the exterior wall of the furnace. The ash-pit chutes 48^a are also normally closed by means of doors 48 having the same form as the doors 47.

One of the ash-pit doors is shown provided with a draft opening which is controlled by means of a damper door 49 of any usual type. Obviously, each of the ash-pit doors may be provided with a damper controlled opening if desired.

From the distributing air chamber 4, the hot air flues or pipes 50 lead as is usual to various portions of the building. The receiving air chamber 5 of course opens into the central air pipe or chamber 3 and into the air chamber formed between the outer wall 2 and the intermediate wall 7. Thus air entering the receiving air chamber passes up around the exterior of the fire-pot and also passes up through the central air chamber 3, this air being discharged into the air distributing chamber 4 and from thence passing to the pipes 50.

The operation of my furnace will be plainly evident from what has gone before. Coal is of course delivered through the coal chutes onto the grate. All air which passes through the furnace enters initially into the receiving air chamber and passes up through the central air flue or chamber, or the air chamber formed between the outer wall 2 and the fire-pot. Thus practically all air is subjected to the action of the fire, and the air which passes up through the central air flue 3 is subjected to the action of the hottest portion of the fire. The air which passes up through the chamber 3 is distributed uniformly into the distributing air chamber by means of the deflector 20 which acts to impede the too rapid upward passage of the air in chamber 3 so that it will be subjected to the action of the fire for a longer period. The heated products of combustion are impeded in their upward passage by the septum 15 but eventually pass into the smoke chamber 10 and thence out through the smoke flue. If it is desired to reduce the draft through the fire pot, the damper 29 may be opened which will cause a large portion of the air entering the ash-pit to pass directly up through the flue 26 into the smoke chamber 10 and thence out through the flue 22. When the damper 29 is closed, it will be evident that all air entering the ash-pit will pass upward through the grates 13 and 14.

Inasmuch as the wall 7 is formed of sections, each section being formed with a socket at one end to receive the end of the next adjacent section, it is obvious that the furnace may be readily put together, and may be readily transported and set up or taken down. The furnace is exceedingly

simple in construction and therefore may be cheaply made and readily set up. The grate thoroughly distributes the coal and therefore makes a uniform fire so as to secure a maximum heating action of the coal. Inasmuch as the air is so thoroughly subjected to the action of the fire, I secure a maximum of efficiency from a minimum amount of fuel.

It will be seen that the outer casing 2, the base section of the wall 7 and the lower end of the wall 6 all seat upon a base ring 51 which is formed to receive and support the lower ends of these members. It will further be seen that the lower end of the wall 6 extends into a central opening formed in the flange 11, the shoulder 12 resting upon a margin of this opening. The assembling of the furnace is therefore very simple and the parts may be readily cast and put together.

Having thus described the invention, what is claimed as new is:

1. In a heating furnace, comprising an annular fire-pot and a surrounding air chamber, two fuel charging chutes extending across the air chamber at the same level and opening through the outer wall of the furnace upon the same side to admit of supplying fuel to the furnace from the front through either chute, one of the walls of the chutes being tangential to the curved wall of the fire-pot to admit of such curved wall deflecting the fuel.

2. In a heating furnace, comprising an annular fire-pot, a surrounding air chamber and a centrally disposed air flue, two fuel charging chutes extending across the air chamber at the same level and opening through the outer wall of the furnace upon the same side, one of the walls of the chutes being tangential to the curved wall of the fire-pot to admit of such curved wall directing the fuel to the rear of the central air flue.

3. In a heating furnace comprising an annular fire-pot and ash-pit, separated by a fuel grate, an air chamber surrounding the fire-pot and ash-pit, and a centrally disposed air flue extending through the ash-pit and fire-pot, two fuel charging chutes arranged at the same level and extending across the air chamber and opening through the outer wall of the furnace on the same side, and two ash chutes in vertical line with the two fuel chutes one of the walls of the two sets of chutes being tangential to the curved walls of the fire-pot and ash-pit, respectively.

4. In a heating furnace, an annular wall having an inturned flange at its lower end, an air flue supported at its lower end upon the inturned flange and extending vertically and formed with spaced outer shoulders, an annular grate supported at its inner edge

upon one of the shoulders and held upon such shoulder by the shoulder next above, a rest upon the wall supporting the grate at its outer edge, and means spanning the space 5 formed between the air flue and annular wall and secured thereto and in contact with the grate to hold the same against vertical movement.

5. In a heating furnace, an outer annular 10 wall having an inner flange at its lower end, a vertical air flue supported upon the inner flange, an annular grate arranged between the flue and annular wall and supported thereby, a septum extending across the space 15 between the flue and annular wall near the upper ends thereof, an annular cap closing the said space and closely fitted to the upper ends of the flue and annular wall, said cap being arched between its inner and outer 20 edges, and a deflector supported on the cap and spaced therefrom and extending over the air flue.

6. A heating furnace comprising a base-ring, an annular wall having an inturned 25 flange at its lower end in the plane of the base-ring and supported thereon, a centrally disposed air flue supported at its lower end upon the inturned flange of the annular wall, a fuel grate supported in the annular 30 space formed between the air flue and wall, the space above the grate forming an an-

nular combustion chamber and the space below the grate forming an annular ash pit, a septum extending across the upper portion of the annular space formed between the 35 air flue and wall, and having a smoke chamber above, an annular cap closing the annular space and supported upon the upper ends of the air flue and annular wall, a deflector supported upon the cap and spaced 40 therefrom and extending over the upper end of the air flue, a casing inclosing the annular wall and spaced therefrom and supported upon the base-ring, said casing projecting above the cap and closed at its upper 45 end to form a distributing air chamber, thimbles extending across the space formed between the casing and annular wall and making close connection therewith, one of such thimbles constitutes a smoke outlet and 50 the other thimble forming a clean-out which is closed at its outer end, a dust flue connecting the clean-out thimble with the ash-pit and arranged in the space formed between the casing and annular wall, and a 55 damper in such dust flue.

In testimony whereof I affix my signature in presence of two witnesses.

JAMES M. BLASHFIELD.
